COMMUNICATION SYSTEM

Harry W. Johnson, Cedar Rapids, Iowa, assignor
to The Turner Company, Cedar Rapids, Iowa,
a corporation of Iowa

Application July 1, 1935, Serial No. 29,233

5 Claims. (Cl. 173—1)

5 My invention relates in general to electrical sound communication systems and it has particular relation to electrical sound communication systems in which two or more stations are employed such as in communication between offices and the like and in which the operator may be at several feet from the transmitting and receiving element or elements of the respective stations.

10 Communication systems constructed in accordance with the usual practice and with which I am familiar have had certain defects. In the devices known to the art in which two or more stations for transmitting or receiving conversation are employed, and in which, during the use of the system, one station might be considered the sending station and the other the receiving station, it has been impossible for the operator at the receiving station to interrupt the operator 15 at the sending station while the operator at the sending station is talking.

20 For instance, it is sometimes desirable to use a communication system of this nature for dictation purposes. It is usually the practice after the completion of the dictation that the person receiving the dictation repeat the material dictated back to the originator for correction. It would be very desirable if the one who has dictated the material could, at will, interrupt the operator reading the material for corrections. In the devices known to the art and with which I am familiar, the operator who is receiving cannot interrupt the operator who is transmitting until the second operator is finished.

25 It is accordingly a general object of my invention to provide an electrical sound communication system in which a plurality of stations are employed, any of which may both transmit and receive.

30 A more specific object of my invention is to provide an electrical sound communication system in which the operator at one station may "cut in" or interrupt the operator at the other station while the second operator is talking on the system.

35 According to my invention, in an electrical sound communication system employing two or more stations, means are provided in the form of an electrical circuit by which the operator at any one station may "cut in" on the operator at a second station while the second operator is talking over the system. In most sound communication systems of this nature it is possible for only one person to talk at one time over the system.

40 If, for instance, an operator at one station is dictating to an operator at a second station and he calls upon the operator at the second station to read back what he has dictated, then in the ordinary system, if the first operator wishes to make a correction, he must wait till the second operator

has finished talking before he can do so. With a system constructed according to my invention the first operator will be able to "cut in" on the second operator whenever he so desires.

45 The novel features that I consider characteristic of my invention are set forth with particularity in the appended claims. The invention itself, however, both as to its organization and its method of operation, together with additional objects and advantages thereof, will best be understood from the following description of a specific embodiment and read in connection with accompanying drawing in which

50 The single figure is a schematic diagram of an electrical sound communication system constructed in accordance with the principles of my invention.

55 The electrical sound communication system shown in the figure includes two stations, indicated generally at 10 and 11, each having a sound responsive unit which may be used either as a transmitter or a receiver. The sound responsive units indicated at 10 and 11 comprise or are comprised of diaphragms 10a and 11a and coils 10b and 11b which are grounded, as indicated at 12 and 13.

60 The two stations are electrically interconnected, by means hereinafter described, to an amplifying circuit indicated generally at 14 and comprising an input connection 16, an amplifying tube 17, a power source 18, and an output transformer 19.

65 It is evident, in a communication system of this nature in which the same sound responsive unit is used to convert the sound waves made by the voice into electrical impulses and also to reconvert the electrical impulses into sound waves, that some means must be employed to change a particular sound responsive unit from the receiving condition to the transmitting condition and back. This is accomplished, in my invention, by the manually operated switches indicated generally at 21 and 22.

70 The switch indicated at 22, however, differs from the switch shown at 21 in that the switch 22 is a double-pole, double-throw switch, the purpose of which is to enable the operator at station 10 to cut in on the operator at 11 whenever the operator at 10 so desires.

75 This is accomplished in the following manner. When the operator at 10 wishes to talk to the operator at 11 he depresses the switch key 23 as indicated by the dotted lines. This operation completes a circuit through the coil 10b of the sound responsive unit 10, through the conductor 26, through one of the input connectors 16 of the amplifying circuit 13, through the amplifying tube 17, the primary winding of coil 18, power supply 18, and ground 20. This am-

plifying circuit increases the intensity of the electrical impulses impressed on the circuit from the transmitting units and in the primary coil of output transformer 19. The electrical impulses 5 impressed in the primary coil of the output transformer 19 are picked up in the secondary coil of the output transformer 19 and transmitted through conductor 21, conductor 28, switch 21 and the coil 11b of the sound responsive unit 11. 10 When the system operates on this circuit the vibrations of the voice impressed on the sound responsive unit at station 10 are converted into electrical impulses through the agency of the diaphragm 10a and coil 10b of the unit 10. The 15 electrical impulses are transmitted through the circuit previously described and are reconverted into sound waves at station 11 through the agency of the coil 11b and the diaphragm 11a of the sound responsive unit at the station 11. 20 When the operator at 10 is finished speaking he releases the switch key 23. If the operator at 11 wishes to speak over the system he then depresses the switch key 29 of switch 21, as indicated by the dotted lines. This operation completes 25 a circuit through the coil 11b of the sound responsive unit 11, through conductor 31, through the switch blade 32, the conductor 33, the conductor 26, through the input connection 16 of the amplifying circuit 14, through the amplifying 30 circuit 14, from the secondary of the output transformer 19 through the conductor 27, the switch 22, through the conductor 24, and the coil 10b of the sound responsive unit 10. When the system 35 is operating on this circuit, then the vibrations of the voice impressed on the sound responsive unit at station 11 are converted into electrical impulses through the agency of diaphragm 11a and coil 11b of the sound responsive unit 11. These electrical impulses are transmitted 40 through the foregoing circuit and are reconverted into sound waves at station 10 through the agency of the coil 10b and diaphragm 10a of the sound responsive unit at the station 10.

However, the operator at station 10 may interrupt 45 the conversation of the operator at 11 at will by depressing the switch key 23 to the position indicated in dotted lines. If the operator at 10 depresses the key 23 during the period when the operator at 11 is talking and is holding the 50 switch key 29 of switch 21 in the depressed position shown in the dotted lines, then the circuit through the coil 11b and conductor 31 to the input side of the amplifying circuit is broken at the switch 22. At the same time a circuit is 55 formed from coil 10b of the sound responsive unit at 10, through the conductor 24, the conductor 26, the amplifying circuit 14, the conductor 27, the switch blade 32, the conductor 31, the switch key 29, and the coil 11b of the sound 60 responsive unit at 11. Therefore, in this manner, the operator at 10 may interrupt the conversation of the operator at 11 whenever he so desires and may thus place station in receiving condition and talk to the operator at 11. It is 65 apparent that the operator at 10 may talk over the system whether the operator at 11 holds the switch key in the position shown by the dotted lines or in the position shown in solid lines.

It is apparent, therefore, that my invention 70 provides a simple two-station or plural station electrical sound communication system that will have varied uses and will be particularly useful for communication between offices and the like.

My invention will have the distinct advantage in that one operator will be able to interrupt an operator at another station at will. Thus, time will be saved, as for instance in the correction of messages or material dictated over the system 5 and then repeated back to the originator.

Although I have shown and described a certain specific embodiment of my invention, I am fully aware that many modifications thereof are possible. My invention, therefore, is not to be 10 restricted except insofar as is necessitated by the prior art and by the spirit of the appended claims.

I claim as my invention:

1. In an electrical communication system, a plurality of stations each having transmitting and receiving means, a circuit for connecting the stations, the circuit having input and output connections, means for selectively connecting the input or the output of the connecting circuit to one of the stations for transmitting and receiving respectively, and other means at one of the other stations adapted to break the circuit at the first station to change it from transmitting to receiving when it is in the transmitting condition. 25

2. In an electrical communication system, a plurality of stations, each having transmitting and sending means, an amplifying circuit connecting the stations, the amplifying circuit having input and output connections, a manually operable two-way switch for selectively connecting the input or the output of the amplifying circuit to one of the stations, and a manually operable double-pole, double-throw switch at one 30 of the other stations adapted to break the circuit at the first station to change it from transmitting to receiving condition when it is in the transmitting condition. 35

3. In an electrical communication system employing a plurality of stations, a connecting circuit for connecting the stations having input and output connections, means at one of the stations for selectively connecting the station to the input or the output of the connecting circuit, and means at the other station for changing the 45 polarity of the connecting means at the first station to change its condition.

4. In an electrical communication system employing a plurality of stations, an amplifying circuit disposed with its connections between the stations having input and output connections, a two-way switch at one of the stations for selectively connecting the stations to the input or the output of the amplifying circuit, and a double-pole, double-throw switch at the other station for changing the polarity of the connecting means at the 55 first station to change its condition.

5. In an electrical communication system including at least two stations, conductors for connecting the stations, an amplifier circuit comprising a tube power supply and output transformer, switch means for connecting the filament or cathode and grid of the tube selectively to one or the other of the stations to place them in transmitting condition and the said switch means also being arranged to connect the other station to the secondary of the output transformer to place it in receiving condition, and other switch means at one of the stations to reverse the polarity of the conductors to change the other station from transmitting to receiving condition when so desired. 65

HARRY W. JOHNSON. 70
